FLIER CONSTRUCTION

Michael J. McHale, Scranton, Pa.

Application July 7, 1949, Serial No. 103,517

4 Claims. (Cl. 57—116)

1

My invention relates to fliers of the type used with spinning machines, and more particularly to a flier block arrangement having improved means for attaching and supporting the flier wires.

The present application, which is a continuation-in-part of my application S. N. 691,103, filed August 16, 1946, now Patent 2,483,320, issued September 27, 1949, relates to a modified form of flier block and flier wire support of the character disclosed in the aforementioned application, together with an improved flier block and flier wire supporting arrangement.

In application S. N. 691,103, filed August 16, 1946, I have disclosed a number of specifically different flier block structures including one form wherein the flier wire support is detachably secured to the flier block by means of the cooperative engagement between a plurality of lugs formed on the block, and complementary recesses formed in the flier wire support. Accordingly, the present application is concerned with the above noted common subject matter, together with an improved flier construction, to be described more fully hereinafter.

In Patent 2,187,862, issued to me January 23, 1940, there is disclosed a flier construction having a flier wire support member in the form of a plate adapted to fit over the head portion of the flier body or block, the plates being attached to the flier body by means of a cap positioned below the plate and attached thereto by spot welding; also in Patent 2,212,299 issued to me August 20, 1940, there is disclosed a flier construction for a bi-partite flier wire support member in the form of complementary sections having semi-circular cut-out portions adapted to seat in a peripheral groove at opposite sides of the flier block. The arms, defined by the cut-out portions, are adapted to overlap and means are provided for engagement with the peripheral flanges of the block whereby the sections of the flier wire support are securely clamped or locked to the flier block; and in application S. N. 729,243, filed February 18, 1947, now Patent 2,483,321, issued September 27, 1949, there is disclosed a flier construction comprising a unitary molded block and wire support, formed from plastic.

I have found, after considerable research and experimentation, that the constructions of my prior patents can be substantially simplified to provide improved operation with marked economies in manufacture, and that improved results can be obtained by reason of certain modifica-

2

tions and/or combinations of the arrangements of the aforementioned patents and patent applications.

An object of my invention is to provide a flier block having improved means for attaching and supporting the flier wire thereon.

Another object of my invention is to provide a flier construction having means whereby the arms of the flier wires are supported in a fixed plane in the vicinity of their points of attachment to the flier block.

Yet another object of my invention is to provide an improved flier construction wherein the flier wires are attached to the flier block by crossing or overlapping the wires in the vicinity of the body portion of the block whereby the arms of the flier wires are maintained in the desired seated position on the block.

Still another object of my invention is to provide an improved flier wire support having means associated therewith adapted for engagement with the body of the block whereby relative movement of the support with respect to the body of the flier is prevented.

A further object of my invention is to provide a unitary molded plastic flier block having flier wire attaching means formed integral therewith, the flier wires and/or a flier wire balancing loop being attached to the block by crossing or overlapping the wires in the vicinity of the body portion of the block.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Fig. 1 is an elevational view, partly in section, showing my improved flier in operative position on a bobbin spindle.

Fig. 2 is a top plan view of the flier wire support used with the flier shown in Fig. 1.

Fig. 3 is a top plan view, showing a flier wire support in operative position on the flier block.

Fig. 4 is a bottom plan view of the flier shown in Fig. 1.

Fig. 5 is a perspective view of the flier block used with the flier shown in Fig. 1.

Fig. 6 is a bottom plan view of a modified form of flier; and

Fig. 7 is a sectional view, taken along line 7-7 of Fig. 6.

The proposed form of flier construction of the present invention, comprises essentially, a flier block in the form of a centrally apertured body member having base and head portions, a peripheral flier wire support member formed on the body of the block between the base and head portions, and a flier wire support adapted to seat on the peripheral support. The flier wire support member, which may be formed from metal or other suitable material, is provided with a central opening adapted to receive the head portion of the block, and is also provided with a plurality of cut-out portions contiguous to the central opening, designed to receive complementary lug members formed on the head portion. In assembling the flier, the flier wire support is placed on the head of the block, with the lug members extending through the cut-out portions, and thereafterwards upon relative rotational movement between the block and the support, the flier wire support is securely clamped to the block.

Referring to the drawings, and more particularly to Fig. 1, there is shown a flier arrangement associated with a bobbin 1, mounted in operative position on a suitable spindle 2, of a conventional winding machine. The bobbin is provided with a head member 3, and a centrally recessed portion 4 adapted to receive a ferrule 5 having an aperture 6 through which the flier foot 7 is inserted in the flier block, designated generally by numeral 8, comprising a centrally apertured body portion 9 and a head portion 10. Between the base and the head portions, there is provided a peripheral flange 11 adapted to form a seat for the flier wire support member, as will be explained more fully hereinafter.

Referring to Fig. 2, the flier wire support, designated generally by numeral 12, is of general rectangular shape and as here shown, is formed from metal. It will be understood that the support may be formed from other materials having the necessary rigidity and adapted for cutting and/or forming. The support is provided with a central opening adapted to receive the head 10 of the flier block, and the body portion is formed with a plurality of cut-out portions 13, designed to receive complementary lugs 14, formed on the head of the flier block, as will be described more fully hereinafter. In order to maintain the arms of the flier wires in desired separated position, the support is provided with diagonally arranged grooves 15 at opposite ends thereof and depressed portions 16 between adjacent grooves.

As will be seen in Fig. 4, the free ends 17 of the support 12 are slotted as at 18, and are turned backwardly and inwardly upon themselves to form flier wire attaching means. Each of the flier wires comprises a central block engaging portion 19, having arms 20, extending outwardly therefrom. It will be noted that the wires are crossed or overlapped as at 21, and that arms 20 are urged into seated position in slots 18 by reason of the tension to which they are sub-

jected when the wires are arranged, as shown, in operative position with reference to the block and its associated flier wire support. The arms of the flier wires, as heretofore noted, are maintained in desired separated position by means of the depressed portions 16 and grooves 15. Portions of the arms in the vicinity of the ends of the support seat in the grooves 15, formed by pressing the material of the support outwardly above the plane of its body portion, and the intermediate portions are separated by the stops 16, formed by pressing the material of the support downwardly below the plane of the body portion of the support.

The flier block (Fig. 5) designed for use with the support 12, comprises a centrally apertured body 9, having a head portion 10, and an off-set foot 7 adapted for insertion through aperture 6 formed in the ferrule 5 of the bobbin 1. The head portion of the block is provided with a plurality of spaced lugs or projections 14, and between the base and head portions, the block is formed with a pair of stepped peripheral flanges 11 and 22, providing supports for the flier wire support member and the flier wires, respectively.

The flier is assembled by inserting the head portion 10 of the flier block through the central opening of the support 12, with lugs 14 coinciding with the cut-out portions 13. Thereafterwards, the block is rotated to bring the lugs to positions intermediate the cut-out portions, thus clamping the flier wire support and the flier block together. The design of the lugs, cut-out portions and the width of the groove between the lower faces of the lugs and the upper face of flange 11, are correlated with respect to the flier wire support whereby a snug frictional fit is attained to securely clamp the parts together, after they are assembled.

In connection with the assembly of the flier, and more particularly the assembly of the flier wire support and the flier block, Fig. 2, which is a top plan view, shows the relative position of the parts after the head 10 of the block has been inserted in the central opening of the support, and prior to rotation of the block or the support to lock the parts together. In the position shown, it will be seen that the lugs 14 are in the cut-out portions 13, which portions terminate in arcuate shaped ends 23 at greater radial distances from the center of the support than the peripheral portions 24 of the central opening in the support. The relative positions of the parts, after rotation of the block or the support, is shown in Fig. 3. It will be seen that the lugs 14 now extend over arcuate portions 24 and, as indicated hereinabove, by reason of the design of the lugs, cut-out portions and the width of the groove between the lower faces of the lugs and flange 11, a snug frictional fit is obtained.

Referring to Figs. 6 and 7, there is shown a modified form of flier, comprising a unitary molded plastic block and flier wire support. In the modification, the flier, designated generally by numeral 25, is formed with a substantially rectangular shaped flier wire support 26, having inwardly turned end portions 27, which are slotted as at 28, to receive the arms of the flier wires. The central body portion 29 of the flier is formed with a head portion 30 and an eccentric foot member 31. As will be seen in Fig. 7, the body portion of the flier is formed with a peripheral flange 32 having an enlarged portion 33, extending outwardly in a direction opposite the off-set foot 31. The purpose of this arrangement

is to balance out centrifugal forces which are generated when the block is rotated, thereby providing a substantially uniform tension on the yarn.

The flier wire support is further provided with integral lugs or projections 34 designed to serve as flier wire fastening or retaining members. In attaching a wire to the support, the wire is looped around one of the lugs 34, as shown, with the arms over-lapped or crossed as at 35, portions of the arms outwardly from the overlap being seated in the slotted portions 28 of the support. By reason of the tension developed in the wire after it is looped about one of the lugs, as above described, the arms are forcibly urged into seated position within the slots of the inturned end portions. Vertical movement of the arms with respect to the support is prevented by the in-turned ends and by the oblong shaped tops 36 of the projections 34.

The flier structure shown in Fig. 6 is intended for use with double flier wires, that is to say, with two arms extending outwardly on opposite sides of the support, or with a single wire. When used with a single wire, as shown, a balancing member in the form of a loop 37 is attached to the lug which would normally receive the second wire. By means of the loop 37 the centrifugal forces generated by the single wire are balanced out when the block is rotated, thus providing uniform tension on the yarn.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention or exceeding the scope of the appended claims.

I claim:

1. A balanced unitary molded plastic flier block comprising a centrally apertured body member having base and head portions, and an off-set foot adapted for insertion into the head of a bobbin, and a peripheral flange on the body member having an enlarged portion in a direction opposite the foot, whereby to balance centrifugal forces generated by said foot when the block is rotated, a flier wire support between the base and head portions of the block, said support having free end portions, each of the free ends of said support having a recess therein adapted to receive an arm of a flier wire, means to attach a flier wire to the support comprising an enlarged lug positioned centrally of the under side of the support, a flier wire having a central lug engaging portion and arms extending outwardly therefrom attached to the support, the arms of the wire being over-lapped in the vicinity of the lug and seated in the recesses at the ends of the flier wire support.

2. A balanced unitary molded plastic flier block comprising a centrally apertured body member having an off-set foot adapted for insertion into the head of a bobbin, a peripheral flange on the body member having an enlarged portion in a direction opposite the foot, whereby to balance centrifugal forces generated by said foot when the block is rotated, a flier wire support formed on the body portion of the block, said support having free end portions, each of the free ends of said support having a recess therein adapted to receive an arm of a flier wire, means to attach a flier wire to said support comprising a pair of

integral lug members positioned along the longitudinal axis on the under side of the support and at points diametrically opposite of the central aperture, a flier wire having a lug engaging portion and arms extending outwardly therefrom attached to the support, the arms of the wire being over-lapped in the vicinity of the lug and seated in the recesses at the ends of the flier wire support.

3. A balanced unitary molded plastic flier block comprising a centrally apertured body member having an off-set foot adapted for insertion into the head of a bobbin, a peripheral flange on the body member having an enlarged portion in a direction opposite the foot, whereby to balance centrifugal forces generated by said foot when the block is rotated, a flier wire support formed on the body portion of the block, said support having free end portions, each of the free ends of said support having a recess therein adapted to receive an arm of a flier wire, means to attach a flier wire to said support comprising a pair of integral lug members positioned along the longitudinal axis on the under side of the support and at points diametrically opposite of the central aperture, a flier wire having a lug engaging portion and arms extending outwardly therefrom attached to the support, the arms of the wire being over-lapped in the vicinity of the lug and seated in the recesses at the ends of the flier wire support.
4. A balanced unitary molded plastic flier block comprising a centrally apertured body member having base and head portions, and an off-set foot adapted for insertion into the head of a bobbin, and a peripheral flange on the body member having an enlarged portion in a direction opposite the foot, whereby to balance centrifugal forces generated by said foot when the block is rotated, a flier wire support between the base and head portions of the block, said support having free end portions, each of the free ends of said support having a recess therein adapted to receive an arm of a flier wire, means to attach flier wires to the support comprising a pair of integral lugs positioned centrally of the under side of the support, a flier wire having a lug engaging section and arms extending outwardly therefrom attached to one of the lugs, the arms of the wire being over-lapped in the vicinity of the lug and seated in the recesses of the adjacent end of the support, and a flier wire balancing member attached to the other lug, whereby to balance the centrifugal forces generated by the flier wire when the block is rotated.
5. A balanced unitary molded plastic flier block comprising a centrally apertured body member having base and head portions, and an off-set foot adapted for insertion into the head of a bobbin, and a peripheral flange on the body member having an enlarged portion in a direction opposite the foot, whereby to balance centrifugal forces generated by said foot when the block is rotated, a flier wire support between the base and head portions of the block, said support having free end portions, each of the free ends of said support having a recess therein adapted to receive an arm of a flier wire, means to attach flier wires to the support comprising a pair of integral lugs positioned centrally of the under side of the support, a flier wire having a lug engaging section and arms extending outwardly therefrom attached to one of the lugs, the arms of the wire being over-lapped in the vicinity of the lug and seated in the recesses of the adjacent end of the support, and a flier wire balancing member attached to the other lug, said member comprising a loop having arms extending inwardly of its closed end, the arms being over-lapped in the vicinity of the lug and seated in the recesses at the end of the support.
